UNITED STATES PATENT OFFICE.

ULYSSES J. BOOCK, OF KINMUNDY, ILLINOIS.

ENSILAGE-PACKING DEVICE.

1,148,569.

Specification of Letters Patent. Patented Aug. 3, 1915.

Application filed November 30, 1914. Serial No. 874,744.

To all whom it may concern:

Be it known that I, ULYSSES J. BOOCK, a citizen of the United States, residing at Kinmundy, in the county of Marion and State of Illinois, have invented certain new and useful Improvements in Ensilage-Pack-
5 ing Devices; and I do hereby declare the following to be a full, clear, and exact de-
scription of the invention, such as will en-
able others skilled in the art to which it ap-
10 pertains to make and use the same.

This invention relates to means for han-
dling ensilage and in particular to devices
for packing ensilage in silos and the like.

15 One of the objects of this invention is to provide an arrangement whereby ensilage can be packed within a silo or other inclo-
sure of any size.

20 Another object of this invention is to provide an arrangement whereby the pack-
ing weight may be shifted to various points within the silo.

25 Still another object of this invention is to provide an arrangement whereby the pack-
ing or assembling of the ensilage is insured,
said packing being derived from a mechani-
cal source.

30 Other objects and advantages of this in-
vention will be more clearly set forth in the
specification and pointed out in the claims.

Similar characters of reference refer to similar parts throughout the specification and drawings, in which,

35 Figure 1 is an elevation of this device as-
sembled for operation, Fig. 2, an end view
of the segmental rack showing means for
locking the operating levers and showing a
pivotal operating arrangement for the
upper portion of this device, Fig. 3, a side
40 view of the gearing arrangement to inter-
mittently operate the drum to this device.
said figure showing the operation at the
moment of starting the drum, Fig. 4 is a
side view showing the above gearing at the
45 moment of the release of the drum, and
Fig. 5 is a view of a modified form of a
drum releasing means.

In Fig. 1 of the drawings, 1 is a drive
50 shaft having the driving pulley 2 mounted
thereon adapted to receive any suitable
source of power, said drive shaft being
mounted through the shaft bearings 3 and 4
suitably attached to any form of support.
A second shaft 1' is also mounted in the
55 bearings 3 and 4 adjacent the drive shaft 1,
upon which is loosely mounted a gear wheel

7 having a shaft sleeve 7' upon which is ro-
tatably mounted a drum 6. A driving gear
8 is rigidly mounted upon the shaft 1 and
meshes with the gear wheel 7 to drive the
same. A lug 9 projects from a suitable sup-
port adjacent to and above the meshing
50 point of the gear 8 and the gear wheel 7,
and a second lug 10 also projects from the
same support adjacent to and below the
meshing point of said gear and gear wheel.
Pivotaly attached as at 12 to a circular
frame 11 carried by the drum 6 is a dog or
latch 13, said dog having a finger 14 de-
pending therefrom at one side of the pivot
70 point which is adapted to engage with the
teeth of the gear wheel 7 to cause the drum
to rotate with said gear wheel. The end of
the dog on the opposite side of the pivot
75 point from that occupied by the finger 14 is
arranged to engage the lug 9, thus forcing
the finger into engagement with the teeth,
while the opposite end of the dog beyond
the finger 14 extends in the path of the lug
10 and serves to disengage the finger from
80 the teeth when said end is moved into en-
gagement with the lug 10, thus permitting
independent rotation of the drum from the
gear 7. The finger 14 is normally held out
of engagement with the teeth of the gear 7
85 by means of a depression spring 15, one end
of which engages the end of the dog 13 in
the path of the lug 9, while the opposite end
thereof engages a lug 16 carried by the
member 11, the tension of said spring be-
ing such as to normally hold the finger 14
90 out of the path of the teeth of the gear 7,
but is not of sufficient strength to overcome
the frictional engagement of the finger with
the teeth.

95 Suitable pulleys 17 and 18 are mounted
from the roof of the silo or like device, over
which passes a cable or rope 19, one end of
said cable or rope being wound around the
drum 6 and the opposite end having at-
100 tached thereto a suitable weight 20. Positioned
from any suitable source above the
drum 6 is a platform 21 having a standard
22 pivotally mounted thereupon, said stand-
ard having rigidly attached thereto by
105 means of flanges or lugs 23, a segmental
rack 24. A spindle 25 having an operating
handle 26 thereon is suitably mounted on
the platform 21 and has rigidly attached
thereto a gear 27, said gear meshing with
110 the segmental rack 24 and adapted to turn
the standard 22 through the medium of the

- segmental rack 24 by the manipulation of the handle 26. A suitable toggle arrangement 28 is pivoted at 29 to the standard 22, the ends of said toggle forming operating levers 30 and 31, said operating levers being arranged to move the toggle arrangement in extended or retracted position and also to shift the extended end of said toggle to a point above or below the horizontal plane, 10 said adjustments being achieved by shifting the levers 30 and 31 and securing them in their adjusted positions through the medium of suitable locking devices 32 and 33 which coöperate with a segmental rack 34, as clearly shown in Fig. 2 of the drawings. The outer end of the toggle 28 has an extended arm 35 in which is pivotally mounted a pair of pulleys 36 and 37, between which operates the cable or rope 19. 15
- 20 For the ready convenience of repairing or renewing the parts of the toggle arrangement, the segmental rack 34 is pivotally mounted as at 38 to the standard 22 and can be suitably locked to said standard at 25 the lower end if desired.
- In the modified form shown in Fig. 5, the drum 39 is rigidly mounted upon a shaft 40, said shaft being suitably sleeved in bearings 41 and 42 projecting from a support 43. 30 The opposite end of the shaft 40 has rigidly secured thereto a gear wheel 44 upon which is formed, near the periphery thereof, a segmental shifting dog 45, the integral end portion of which is provided with teeth 46, to correspond with the teeth in the gear wheel 44. A drive shaft 47 mounted in bearings 48 and 49 projecting from a support 50 is positioned adjacent the gear wheel 44, one end of the drive shaft 47 having a driving pulley 51 rigidly attached thereto, the opposite end of said shaft having a gear 52 mounted thereon in such manner as will cause the gear to rotate with the shaft and at the same time permit the gear to slide 45 longitudinally of the shaft, said gear being normally in mesh with the gear 44. In order to disengage the gear 52 from the gear wheel 44, a peripheral flange 53 is secured to the inner face of the gear 52 and extends 50 into the path of the shifting dog 45, so that when the flange engages the dog, the gear 52 will be moved bodily longitudinally of the shaft 47 until the teeth of the gear 52 is moved out of mesh with the gear 44, thereby 55 permitting the drum 39 to freely rotate. The gear 52 is returned to and normally retained in meshing operation with the gear wheel 44 by means of a coil spring 54 mounted between the bushing 48 and the gear 52. 60 In the operation of this modified form, the gear 52 is thrown out of mesh by means of the segmental dog 45 operating against the flange 53, said gear 52 being reseated into meshing engagement with the gear wheel 44 65 by means of the spring 54 as soon as the segmental dog 45 passes beyond the flange 53.
- In operation, my device is suitably attached to the exterior of the upper portion of a silo or the like adjacent the door or window therein, so that the toggle can extend within the silo to manipulate the cable or rope 19 and shift the weight to various points within the silo. Upon the rotation of the shaft 1, through the medium of the 75 drive pulley 2, the gear wheel 7 is rotated through the medium of the gear 8 and carries with it the member 11 through the medium of the dog 13 which is locked by friction with the teeth of the gear wheel 7, thereby 80 rotating the drum 6 which winds the cable or rope 19 thereon to lift the weight 20. When the dog 13 rotates around and strikes the projection 10 the dog is lifted from out of engagement with the teeth of the gear wheel 7, thereby releasing the drum 6 to allow the weight to fall upon the ensilage within the silo or the like, thereby 85 packing it. This operation returns the dog 13 to its initial position which operation 90 causes it to strike the projection 9 and re-engages the finger 14 with the teeth of the gear wheel 7, ready for the next operation. 95
- By intermittently raising and releasing the weight in the manner shown and permitting it to descend with force upon the ensilage within the silo, said ensilage will be firmly packed within the silo and by providing the toggle arrangement and pivotally mounting the same in the standard 22 and 100 also by swivelly mounting the standard, the weight can be shifted to any point within the silo as may be desired without interfering with the operation of the device or the introduction of the ensilage therein. It will 105 likewise be seen that by properly locating the drum and parts to operate the same, it can be driven from parts of the machine used for disintegrating and preparing the ensilage. 110
- Having described my invention, what I claim as new and desire to secure by Letters Patent, is:—
1. An ensilage packing device, comprising a drum, a cable adapted to be wound upon the drum, means to suspend one end of the cable in an inclosure, a weight attached to that end of the cable within the inclosure, means to intermittently rotate said drum, means to intermittently release the drum 115 from the rotating means, and a toggle arrangement to shift the weight to various points within the inclosure. 120
  2. An ensilage packing device, comprising a pair of driving gears, means to apply power to said driving gears, a drum independently rotatable of said gears, means carried by the drum adapted to intermittently engage one of the gears to cause the drum to rotate therewith, means to operate said en- 125 130

- gaging means to cause the same to engage with or disengage from said gear, a cable adapted to be wound upon said drum when rotated with the gear and unwind therefrom 5 when the drum is released, a weight at the opposite end of the cable, means to suspend the cable in an inclosure, and additional means to control the position of the weight within the inclosure.
- 10 3. An ensilage packing device, comprising a pair of intermeshing gears, means to drive said gears, a drum independently rotatable of said gears, a dog pivoted to the drum, means to intermittently engage the dog with 15 one of the gears or disengage the same therefrom, a cable adapted to be wound upon said drum, a weight carried by the cable, and means to suspend a portion of the cable and the weight within an inclosure.
- 20 4. An ensilage packing device, comprising the combination with a drum, means to intermittently rotate and release said drum, a cable coöperating with said drum, a weight carried by the opposite end of the cable
- adapted to be intermittently raised and lowered when the drum is intermittently operated, of an adjustable toggle arrangement coöperating with the cable to shift the weight to various parts of an inclosure and means to swing the toggle arrangement laterally. 25
5. An ensilage packing device, the combination with a drum, means to intermittently operate the drum, a cable coöperating with the drum and a weight attached to the cable 30 adapted to be raised and lowered by the operation of the drum, of a toggle arrangement coöperating with said cable, and means to operate the toggle arrangement to shift the weight to various points within an inclosure. 35

In testimony whereof I have signed my name to this specification in the presence of two subscribing witnesses.

ULYSSES J. BOOCK.
